UNITED STATES PATENT OFFICE.

EDWARD SCHWARTZ, OF CHICAGO, ILLINOIS, ASSIGNOR TO THE PELOUZE MANUFACTURING COMPANY, OF CHICAGO, ILLINOIS, A CORPORATION OF ILLINOIS.

DESIGN FOR AN ELECTRICALLY-HEATED TOASTER.

43,023.

Specification for Design.

Patented Sept. 10, 1912.

Application filed July 5, 1912. Serial No. 707,913. Term of patent 14 years.

To all whom it may concern:

Be it known that I, EDWARD SCHWARTZ, a citizen of the United States of America, and a resident of Chicago, in the county of Cook and State of Illinois, have invented a new, original, and ornamental Design for Electrically-Heated Toasters, of which the following is a specification, reference being had to the accompanying drawing, forming part thereof.

The figure is a perspective view of an electrically heated toaster, showing my new design.

I claim:—

The ornamental design for an electrically heated toaster, as shown.

EDWARD SCHWARTZ.
